SHEET SEPARATOR

Georg Spiese, Leipzig, Germany

Application September 13, 1938, Serial No. 229,788
In Germany September 18, 1937

6 Claims. (Cl. 271—27)

The present invention relates to a device for lifting off the uppermost sheet of a staple or pile of sheets of paper or similar materials by means of a sheet catcher, which is moved upward and forward and, reversely, rearward and downward.

The known devices for performing this combined gripping movement in sheet layers are of relatively complicate construction and comprise a great number of individual parts, so that the manufacture of the same is expensive and the parts are rapidly worn. Moreover, the known devices need careful attendance when in operation and frequently cause breakdown of service.

Through the present invention the movements of the sheet catcher needed for lifting off the sheets are achieved in a simple manner by means of very few parts, whereby simultaneously a faster working of the device is achieved.

For this purpose the novel sheet catcher is for its movement in two points carried and guided by swivel arms or levers. According to the invention the sheet catcher may, in order to enable it to perform the required movements, for instance on the one hand be carried and controlled by a swivel arm, which is positively controlled by an eccentric, a cam disc or similar means, and on the other hand by one or more additional swivel arms. The inventive idea may for instance advantageously be carried into effect by arranging the sheet catcher on two arms, which are swingable about stationary shafts, and guide the sheet catcher in such a manner by means of the said arms that it performs its movements between the two shafts, which are arranged one above the other. According to another embodiment of the invention the sheet catcher is on one side guided through a link of an articulated parallelogram or pantograph, arranged above the pile of sheets. The former embodiment is particularly well suited for sheet catchers, which attack the front edges of the sheets, whilst the other embodiment is adapted to attack the pile in any point of the same, in the direction in which the sheets are moved. The last mentioned device may also be displaceably arranged above the pile of sheets, for instance in slide guides. In both embodiments the various phases of the movements can be freely observed, and all movable parts are easily accessible.

Another feature of the present invention is that the sheet catcher is on one side guided by an arm or a link of a pantograph, pivotally arranged on a stationary shaft, in such a manner that the suction catcher at the beginning of its upward

movement, in order to avoid undesired displacements, is moved through a short distance in a direction opposite to that in which the sheets are conveyed.

In order that the sheet catcher or the suction catcher may perform adjustable tipping movements immediately above the pile of sheets, the suction catcher is according to the invention linked to the suction catcher and its position is determined by a spring and two stops on the sheet catcher and on the suction catcher, respectively, whilst a second abutment arm on the suction catcher cooperates with a stop, which is rotatable or adjustable also when the apparatus is working.

Two embodiments of the invention are illustrated schematically by way of example in the accompanying drawings. All parts, which are not necessary for the understanding of the invention, have been omitted.

Fig. 1 shows the most important parts of a sheet catcher according to the invention in lateral view.

Fig. 2 is a plan view of the same parts.

Figs. 3-5 show three successive working steps of the means for moving the sheet catcher during the lifting of a sheet.

Fig. 6 shows diagrammatically the movements of the means which move the sheet catcher in the form of a simple pantograph.

Fig. 7 is an elevational view of the moving means showing these means with the sheet catcher in the position for suction.

Fig. 8 is a plan view of the same arrangement.

Figs. 9 and 10 show the means for moving the sheet catcher in the other embodiment of the invention, in two additional successive working stages, including a driving arm and a link system comprising a pantograph.

In Figs. 1-6, showing the first embodiment of the invention, 1 denotes the pile of sheets, 2 the abutments for the pile, 3 the separation blower and the driving drum 4, which feeds the sheets to the stop numbers of the machine by means of conveyor belts 6, which run over the supply table 5. The drum 4 shown is a suction conveyor drum, but the same may of course be replaced by a conveyer drum of the usual kind, to which the delivered sheets are pressed by controlled pressure rollers, so-called timed rollers. In as far the device is known. The shaft 7 of the roller 4 is arranged in bearings in the walls of the machine frame 8, which also carry a control shaft 9, a so called one-turn shaft, which like the drum 4 may be driven by any convenient means (not shown). On the control shaft 9 an eccentric 10 is located.

against which the roller 11 of a two-armed lever 12 is pressed by means of a spring 13. The lever 12 is pivotally arranged on a bolt 14, which is fixed in the wall 8 of the frame. The other end of the lever 12 is connected to one end of a link 15, the other end of which is connected to a rocking lever 16, which is arranged on the shaft 7 of the drum 4, and guides the link 15 in such a manner that, when the roller 12 reciprocates, the link 15 is reciprocated in the space between the bolt 14 and the shaft 7. The link 15 has a downwardly directed elongation 17, which extends beyond the joint between the rocking lever 16 and the link 15 and together with the latter forms the sheet catcher. A link system 12, 15, 16, 17 is arranged on both sides of the pile 1 and the drum 4. The arms 17 of the rocking levers 16 carry a rotatable tubular suction rod 19, which again carries series of suction catchers or grippers 18. The rod 19 has a projection 20 and stands under the influence of a torsion spring 21, which is located on the rod. The spring strives to move the rod 19 in such a direction that the projection 20 of the same abuts against a stop 22 on the part 17 of the lever 16. The rod 19 also carries an arm 23, which cooperates with an abutment bolt 24, adjustably arranged in the wall 8 of the frame.

In the position shown in Fig. 3 the suction nozzles 18 contact with the surface of the pile and are held in a position in which their suction faces form an angle with the pile surface, because the arm 23 of the suction rod 19 rests on the stationary bolt 24. In the course of the movements of the link system the nozzles 18 are lifted from the pile 1 and under the influence of the spring 21 moved into a vertical position, until the stops 20, 22 of the suction rod 19 and the arm 17 of the lever 15 abut against each other. Fig. 1 shows this position of the suction rod 19.

During the continued movement the link system is brought into the positions shown in Figs. 4 and 5. Fig. 4 shows the position of the links in which the front edge of the sheet is lifted over the abutment mouldings to the pile, and Fig. 5 shows the final position, in which the nozzles 18 deposit the sheet on the suction drum 4, which is driven by the belts 6.

Fig. 6 shows diagrammatically the curves of movement of the joints of the link system and the substantially horizontal position of the suction nozzles during their forward movement.

The members 12, 15, 17 of the link system are hollow and connect the tubular suction rod 19 with the conduit leading to the suction pump. The joints connecting these members are therefore also made hollow.

In the embodiment shown in Figs. 7-10 a suction catcher 25 is directly attached to one end of a carrier 26 forming the sheet catcher, the other end of which is pivotally connected to a roller arm 27. The other end of the arm 27 is pivotally connected to a bolt 28, fixed to the wall 8 of the machine frame, and the roller 29 en-

gages the periphery of the eccentric 10, which is arranged on the control shaft 9. The sheet catcher is also connected to the arm 30 of a lever 31, which is guided by rocking levers 32, 33, pivotally connected to the wall 8 of the frame. 5

In this embodiment all joints of the link system are located above the pile 1, so that the system can be made slidably and moved over the pile, if desired in the direction in which the sheets are moved, so that the suction nozzles 25 may attack the sheets in any point. Fig. 9 shows the link system in an intermediate position and Fig. 10 in the other final position. In the latter figure the path described by the suction members is indicated by the curve 34. 15

I claim:

1. A device for lifting off the uppermost sheet from a pile of sheets comprising a sheet gripper, a pair of levers cooperating with said gripper, means for positively moving one of said levers, and at least one abutment against which said other lever abuts to move the said other lever, said levers rocking around two points to impart an upward and forward and reversely rearward and downward movement of the gripper to feed 25 the sheets one by one from the pile.

2. A device according to claim 1, in which the means and the abutment comprise two stationary shafts and the movement of the gripper takes place between the two shafts. 30

3. A device according to claim 1, in which a link of a pantograph control is provided to guide the gripper on one side.

4. A device according to claim 1, in which means are provided for sliding the device over 35 the pile of sheets and permitting the gripper to grip the pile in any desired point in the direction of movement of the sheets.

5. A device according to claim 1, in which a rocking lever and a stationary shaft are provided 40 so that the sheet gripper is guided on one side in such a manner that the gripper when its upward movement begins, performs a small movement in a direction opposite to that in which the sheets are moved. 45

6. A device for lifting off the uppermost sheet from a pile of sheets comprising a sheet gripper, a pair of levers cooperating with said gripper, means for positively moving one of said levers, at least one abutment against which said other lever abuts to move the said other lever, said levers rocking around two points to impart an upward and forward and reversely rearward and downward movement of the gripper to feed the sheets one by one from the pile, a suction catcher linked 55 to the sheet gripper, a spring to determine the position of the suction catcher, two stops on the suction catcher and the sheet gripper respectively and a pair of stop arms, one attached to the suction catcher and cooperates in such a manner 60 with the other stop member that the suction catcher can perform an adjustable tilting movement directly above the pile of sheets.

GEORG SPIESS.
